Attorney, Agent, or Firm—DeWitt Ross & Stevens

[57] **CLAIM**

The ornamental design for a combined mitten dryer and warmer, as shown and described.

DESCRIPTION

FIG. 1 is a perspective view of a combined mitten dryer and warmer showing my new design;

FIG. 2 is a top plan view thereof;

FIG. 3 is a bottom plan view thereof;

FIG. 4 is an end elevational view thereof, the opposite end being a mirror image;

FIG. 5 is a side elevational view thereof, the opposite side being a mirror image;

FIG. 6 is a perspective view of a second embodiment thereof;

FIG. 7 is a perspective view of a third embodiment thereof; and,

FIG. 8 is a perspective view of a fourth embodiment thereof. The mittens shown in broken lines and arrow in FIGS. 1, 6, 7 and 8 are shown for illustrative purposes only and form no part of the claimed design.
